UNITED STATES PATENT OFFICE.

IRA B. SMITH, OF BRISTOL, CONNECTICUT, ASSIGNOR TO THE BRISTOL
BRASS AND CLOCK COMPANY, OF SAME PLACE.

DESIGN FOR A SPOON.

SPECIFICATION forming part of Design No. 24,433, dated June 25, 1895.

Application filed March 14, 1895. Serial No. 541,810. Term of patent 7 years.

To all whom it may concern:

Be it known that I, IRA B. SMITH, a citizen of the United States, residing at Bristol, in the county of Hartford and State of Connecticut, have invented and produced a new and original Design for a Spoon, of which the following is a specification, reference being had to the accompanying drawings, forming a part thereof.

10 Figure 1 is a plan view of a spoon, showing my design; and Fig. 2 is a reverse plan view of the same.

15 My invention relates to the design for the handle, the spoon bowl not being new with me.

15 A designates the bowl of a spoon.

The handle B has a narrow portion 3 with smooth edges, and the entire handle grows gradually wider as it recedes from the bowl to a point near its end where its edges draw in 20 and the handle terminates with a rounded end as shown. The smooth edges of the narrow portion 3 merge into the broader portion 4. Upon the top face of the handle, conventional scroll and leaf ornaments 6 extend inwardly

from the scalloped edges and harmonious ornaments 7 are on the middle of the narrow portion 3 contiguous to the broader portion, but do not extend down to the neck or narrowest part of said narrow portion 3, which for its major length is left perfectly plane 25 and smooth. On the reverse or under side of the handle the conventional scroll and leaf ornaments 8 are arranged with the scrolls overlapping, shingle fashion, so as to show only one end of the several scrolls. The end scroll 30 9 shows both of its ends and extending inwardly from it are three leaflets 10 while the central ornaments 11 at the narrow end of the broader scalloped edge portion has the effect of connecting the scroll and leaf ornaments of 35 40 the opposite edges.

What I claim is—

The design for the handle of a spoon, substantially as shown and described.

IRA B. SMITH.
